CLAIM

The ornamental design for a combined faucet body and spout, as shown and described.

DESCRIPTION

FIG. 1 is a front top perspective view of a combined faucet body and spout showing our new design;

FIG. 2 is a rear top perspective view thereof;

FIG. 3 is a top plan view thereof;

FIG. 4 is a front elevational view thereof;

FIG. 5 is a left side elevational view thereof;

FIG. 6 is a right side elevational view thereof; and,

FIG. 7 is a rear elevational view thereof.

The broken line showings of a handle and aerator in FIG. 1 are for purposes of illustration only and form no part of the claimed design.
